(57) **CLAIM**

The ornamental design for a teething device, as shown and described.

DESCRIPTION

FIG. 1 is a perspective view of a teething device showing our new design;

FIG. 2 is a perspective view of the teething device of FIG. 1; FIG. 3 is front elevational view of the teething device of FIG. 1;

FIG. 4 is a rear elevational view of the teething device of FIG. 1;

FIG. 5 is a right side elevational view of the teething device of FIG. 1, the left side elevational view being a mirror image of the right side elevational view; and,

FIG. 6 is a top plan view of the teething device of FIG. 1, the bottom plan view being a mirror image of the top plan view. The broken lines illustrate portions of the teething device which form no part of the claimed design.
